UNITED STATES PATENT OFFICE.

MAXWELL S. HART, OF NEW BRITAIN, CONNECTICUT, ASSIGNOR TO THE HART & HUTCHINSON COMPANY, OF NEW BRITAIN, CONNECTICUT, A CORPORATION OF CONNECTICUT.

LOCK.

1,181,977.

Specification of Letters Patent.

Patented May 2, 1916.

Application filed June 17, 1913. Serial No. 54,928.

To all whom it may concern:

Be it known that I, MAXWELL S. HART, a citizen of the United States of America, residing at New Britain, Hartford county, Connecticut, have invented a new and useful Lock, of which the following is a specification.

My invention relates to a lock construction which is particularly useful in connection with sheet metal locker doors as shown herein, but which is not, in its broadest aspect, limited thereto.

My object is to provide a simple compact durable and exceedingly effective locking device.

In the accompanying drawings: Figure 1 is a sectional view of a portion of a door with certain lock parts shown in front elevation and in unlocked position. Fig. 2 is a similar view of the lock parts in locked position. Fig. 3 is a section on the line 3—3 of Fig. 1. Fig. 4 is a view similar to Fig. 1 showing a modification. Fig. 5 is a section on the line 5—5 of Fig. 4. Fig. 6 is a front view of a part of a door with parts of the lock mechanism shown in Figs. 1 to 3 removed therefrom. Fig. 7 is an elevation of the inside of a lock case showing its locking bolt, and key-operated cam. Fig. 8 is a perspective view of the key operated cam.

1 represents a door especially adapted for lockers. In this instance, the door is made from sheet steel and provided with a hollow stile 2 or border which is extended around the door to form a sunken panel in the center. 3 represents the door casing. In this particular instance the door is provided with three locking bolts which are arranged to engage the casing 3 at the side, top and bottom. These bolts are indicated respectively at 4, 5 and 6. The door locking bolt 4 is in the form of a hook, which may be withdrawn into the housing formed by the hollow door stile 2, see Figs. 1 and 6, or may be projected therefrom as indicated in Fig. 2. In this last mentioned figure, the bolt 4 is shown as projected through an opening in the door casing so as to be hooked back of the same thus preventing the casing from being pried away from the edge of the door. The door locking bolts 5 and 6 are also hidden in the housing or stile 2 and project into suitable keeper plates or openings in the upper and lower parts of the door casing,

see Fig. 6. In one form of construction the hooked bolt 4 is carried by an oscillating member 7 pivoted to the door at 8 while the bolts 5 and 6 are respectively carried by the oscillating member at opposite sides of the pivot 8, whereby as the part 7 is oscillated in one direction, the bolts 4, 5 and 6 will all be withdrawn as shown in Figs. 1 and 6, and when oscillated in an opposite direction, will all be projected as shown in Fig. 2. I have devised an exceedingly simple and effective means for operating and controlling the locking bolts, which means is so compact that it may be largely or entirely contained within the relatively small and thin door hollow stile 2. This means comprises a manually movable lock case 9. In this instance the lock case is mounted to oscillate, and this oscillating movement is utilized to operate the bolts.

By referring to Figs. 1 and 2, it will be seen that the lock case 9 may have a connection with one of the bolts, so that the movement of the case 9 will move all of the bolts. In the particular form shown, the case 9 has an offset 10 which has an opening or slot 11 therein into which slot may project a pin 12 carried by the bolt 6. If now the lock case 9 is moved from the position shown in Fig. 1 to that shown in Fig. 2, the bolt 6 will be moved downwardly, and this movement will, through the medium of the part 9, simultaneously project the bolt 5 upwardly and the hooked bolt 4 forwardly, thus locking the door.

The lock case 9 in its preferred form rigidly carries an outwardly projecting hollow hub or sleeve 14 which may pass through a cap or plate 15.

16 is a suitable handle or knob which in this instance is tubular, the outer end being flared to provide a grip, the inner end sliding snugly over the sleeve 14 and projecting into the cap 15 to provide a suitable bearing. The knob 16 is secured rigidly on the sleeve 14 in any suitable manner as by a screw 17.

18 is a spacer means or washer between the inside of the cap 15 and the outside of the lock case 9 which may be provided if the case is so spaced from the cap 15 as to require a spacer element. The turning of the handle or knob 16 will oscillate the lock case 9 and hence operate the aforesaid door locking bolts in the manner described.

- 19 is a bolt of any suitable type carried by the lock case 9 and arranged to be operated by a suitable key. This bolt 19 is arranged to be reciprocated from the solid line position to the dotted line position indicated in Fig. 7, and is, of course, provided with suitable guides. 20 is a cam-arm which projects into a suitable notch 21 in the tail of the bolt 19. This cam arm 20 is located within the lock case and is provided with an outwardly extending shank 22 which carries the disk 23 at its outer end, said disk having a key slot therein.
- 24 is a recess in the cam-arm 20 which receives the forward end of a key, the said key being inserted through the slot in the disk 23 and preferably guided into the slot 24 by a longitudinal groove in the shank 22.
- 20 Any suitable tumbler mechanism (shown in dotted lines) may be provided for holding the bolt 19 against movement until said tumblers have been properly positioned. It should be understood that the particular key operated mechanism for controlling the bolt 19 may be of any appropriate design or construction.
- In the particular form shown in the drawings, when the bolt 19 has been fully retracted, as shown in Fig. 7, the turning of the key is checked because the length of the cam-arm 20 is such that it cannot be turned in a clockwise direction to a sufficient extent to remove it from the notch 25 in the tail of the bolt. Hence, while the door is unlocked, the key remains in the lock. When the key is turned back to project the bolt 19 it will then line up with the notch 25, in the rolled-in edge of the sleeve 14, and may then be withdrawn.
- When the bolt 19 is projected, as shown in Fig. 2, it will stand between two abutments. In this instance, one abutment is represented by the wall of the cap 15 adjacent to the end of said bolt and the other abutment is the part 26. In this instance the part 26 is a bolt, stud or rivet, utilized to secure the cap 15 in place, 27 indicating a companion bolt used for that purpose. If a proper key is inserted in the key-slot, when the parts stand as shown in Fig. 2, and said key is turned in a clockwise direction, it will first retract the bolt 19 freeing it from abutment 26 so that a continued rotation of the key will move the lock case 9 to the position indicated in Fig. 1, simultaneously withdrawing the door locking bolts 4, 5 and 6. When the user desires to again lock the door, he will first rotate the lock case 9 back to the door locking position shown in Fig. 2, and then project the bolt 19 back of abutment 26.
- In Figs. 1, 2, 3, 6 and 7, I have indicated a construction in which the locking bolts are mounted independently of the lock case 9, whereas in the modification shown in Figs. 4 and 5, I have shown the hooked locking bolt 4^a as mounted directly on the lock case 9^a and have shown the locking bolts 5^a and 6^a as being pivotally connected to wings 9^b—9^c on opposite sides of said lock case, otherwise the construction and arrangement of parts may be understood to be substantially as shown in the other views.
- The stile in which the various parts are located constitutes a hollow housing designed to be located along the freeing edge of the door, and the cap 15 constitutes in effect part of the housing when the parts are assembled. The cap may be and preferably is dished at its rear side so as to be slightly offset from the housing to give the effect of an escutcheon plate, although this is not essential in all cases. I have shown my invention in certain preferred forms for use in connection with sheet metal lockers, appreciating that a variety of changes may be made therein for this purpose and other locking purposes without departing from the spirit and scope of this invention.
- What I claim is:
1. In a lock for doors and the like, a locking bolt, a movable lock case operatively connected therewith whereby the movement of said case will move said bolt, and a handle for manually moving said lock case, and key-controlled means carried by said lock case to hold it against movement in a direction to withdraw the locking bolt, said lock case having a key passage extending through said handle.
  2. In a lock for doors and the like, a locking bolt, a lock case mounted to oscillate and operatively connected with said locking bolt whereby the oscillation of the lock case will move the locking bolt, a handle for pivotally supporting said lock case and for manually oscillating said lock case and moving the bolt carried thereby, another bolt carried by said case arranged to hold said lock case against movement by said handle in one direction with key-controlled means for retracting said last mentioned bolt to release the lock case to permit the same to oscillate in a direction to withdraw said locking bolt with a key passage through said handle.
  3. In a lock for doors and the like, a door having a hollow stile, a locking bolt arranged within the stile and projectable therefrom for door locking purposes, a lock case also housed within said hollow stile and mounted to oscillate therein, said lock case being operatively connected to said locking bolt to move the same by the movement of said case, and a handle rotatable concentrically with said case for manually moving said lock case relatively to said stile, a key operable means in said lock case

for locking the latter against movement, said handle having a key passage leading thereto.

4. In a lock for doors and the like, a door having a hollow stile, a locking bolt arranged within the stile and projectable therefrom for door locking purposes, an oscillating lock case also housed within said hollow stile, said lock case being operatively connected to said locking bolt to move the same by the movement of said case, a handle mounted in said stile and connected concentrically to said case for manually moving said lock case relatively to said door, key operable bolt mechanism carried within said lock case, said handle having a key-way leading thereto.

5. In a lock for doors and the like, a locking bolt, a movable lock case operatively connected therewith whereby the movement of said case will move said bolt, and a handle for manually moving said lock case, and key-controlled means carried by said lock case to hold it against movement in a direction to withdraw the locking bolt, said lock case having a key passage extending through said handle, a key therefor with means for preventing the removal of the key from said lock case when the latter stands in the position in which the door locking bolt is retracted.

6. In a lock for doors and the like, a housing arranged to be located at the free edge of a door, a hooked oscillating door locking bolt mounted within said housing and arranged to be projected therefrom, a lock case mounted to oscillate in said housing and operatively connected with said door locking bolt, a handle sleeve carried concentrically by said lock case and having a key passage into said lock case, said sleeve projecting through one wall of said housing and supported thereby, a handle having a passage therethrough and mounted on the outer part of said sleeve, and means carried

by said lock case and key-controllable for holding said lock case against movement in one direction.

7. In a lock for doors and the like, a lock mechanism, a hollow key hub therefor, a key-operable bolt therefor, an operating handle secured to said key hub for manually moving said case, and a door locking bolt operatively connected to said case, said key operable bolt being carried by said case to lock it against movement.

8. In a lock for doors and the like, a movable lock case, a hollow key hub carried thereby, a handle secured to said key hub for manually operating the lock case, the face of said handle being opened to expose the end of said hub, said hub having a key-way therethrough, and a key operable case locking dead bolt carried by said case to lock it against movement.

9. In a lock for doors and the like, an operating handle, a key receiving member mounted to rotate therein, a door locking bolt, lock mechanism including a movable part, a dead bolt movable relatively to said movable part, and operative connections between the key receiving member and said dead bolt, said operating handle being operatively connected to said movable part whereby the same may be moved by said handle.

10. In a lock for doors and the like, an open ended handle, a lock structure secured thereto, a locking bolt operated thereby by the movement of the lock structure, a rotatable key member carried by the lock structure and projecting through the handle, a bolt carried by the lock structure and operable by a key, and means engageable by said bolt for holding the lock structure against movement when the door is locked and when said key member has been rotated in one direction.

MAXWELL S. HART.
